CLAIM

The ornamental design for a bottle lid as shown and described.

DESCRIPTION

FIG. 1 is a top, front and left side perspective view of a bottle lid, showing my new design;

FIG. 2 is a bottom, rear and right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an exploded perspective view of the bottle lid shown in FIG. 1. The broken lines in the drawings depict portions of the bottle lid that form no part of the claimed design.

1 Claim, 9 Drawing Sheets
